[57] CLAIM

The ornamental design for a cap for timing chain cover, as shown and described.

DESCRIPTION

FIG. 1 is a perspective view of a cap for timing chain cover showing my new design;

FIG. 2 is a front elevational view;

FIG. 3 is a rear elevational view;

FIG. 4 is a side elevational view;

FIG. 5 is a top plan view;

FIG. 6 is a bottom plan view;

FIG. 7 is a perspective view indicating the position of placement when in use.

The broken line showing of an engine is for illustrative purposes only and forms no part of the claimed design.

FIG. 1

FIG. 2

FIG. 3

FIG. 4FIG. 5FIG. 6
